MOTOR TRUCK

Theodore Ornas, Jr., Fort Wayne, Ind., assignor to International Harvester Company, a corporation of Delaware

Filed Oct. 22, 1965, Ser. No. 87,785

Term of patent 7 years

(Cl. D14—3)

I claim:

The ornamental design for a motor truck, substantially as shown.
